SANITARY TOOTH BRUSH HOLDER

Filed March 23, 1934

UNITED STATES PATENT OFFICE

2,046,606

SANITARY TOOTH BRUSH HOLDER

Alfred F. Borba, San Leandro, Calif.

Application March 23, 1934, Serial No. 717,020

5 Claims. (Cl. 312—112.5)

The invention relates to devices such as small brackets and the like which are adapted for the support of tooth brushes, paste tubes, powder cans, etc., and which are generally arranged for mounting on the usual bathroom wall at the convenience of the user.

An object of the invention is to provide a holder of the character described which will shield the brushes supported thereon against dust and the like and will at the same time provide a circulation of air over the brushes to insure a sanitary drying thereof.

Another object of the invention is to provide a plurality of individual hoods or compartments for the brush heads and to afford in cooperating relation with the compartments an improved brush and tube support for facilitating the introduction and removal of the brush to and from the holder.

A further object of the invention is to provide a holder of the character described which will be especially compact in its arrangement and yet not over-crowd the members carried thereby or interfere with the latter's free movement to and from an attached position.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to said drawing:

Figure 1 is a front elevation of a holder constructed in accordance with my invention and broken away over a portion to show the interior thereof.

Figure 2 is a rear view of the holder shown in Figure 1.

Figure 3 is a transverse sectional view of the holder shown in Figure 1, taken substantially on the plane of the line 3—3 of Figure 2.

Figure 4 is a front elevation of a modified form of the invention.

Figure 5 is a longitudinal sectional view of the holder shown in Figure 4, and taken substantially on the plane of the line 5—5 of Figure 4.

Figure 6 is a transverse sectional view of the holder shown in Figure 4 and taken substantially on the plane of the line 6—6 of Figure 4.

With reference to the drawing the holder 11 of my invention comprises a supporting member

12 which is formed with a substantially flat supporting portion 13 arranged at the rear side 14 thereof for mounting against a supporting surface such as the room wall 15. Formed preferably integral with the portion 13 and extending from the top 16 thereof into spaced superimposed relation to the forward surface 17 thereof, is a hood portion 18 which defines with the surface 17 an inverted covered receptacle for the brushes 19. In the present embodiment the holder is adapted to support two brushes and in accordance with this number, the hood and surface 17 are preferably interconnected with a partition 21 serving to divide the aforesaid receptacle into a pair of individual compartments 22 for the brush heads 23.

Support of the brushes is here arranged with the head portions 23 extended into the compartments 22 and with the brush handles 24 depending from the compartments in covering relation to the forward surface 17 of the main holder member. As a convenient feature of the holder, the brush handles may be extended below the lower end 26 of the surface 17 to thereby space the handles from the room wall for ready grasping. Means for so mounting the brushes here include a pair of spring clip members 27 which are affixed to the surface 17 centrally of the compartments and are arranged for the receipt and resilient gripping of the brush handles. As an important feature of this arrangement the clip members are disposed below the lower edge 28 of the hood so as to afford visibility thereof to the user and thereby facilitate the correct positioning and attachment of the brushes.

In addition to the use of the holder for supporting the brushes, I provide for the convenient attachment of a paste tube 29 or the like to the holder so as to afford in a single, handy unit the requisites for brushing one's teeth. While thus making the holder more complete in its purpose, I have nevertheless arranged for the support of the paste tube in a manner not interfering with the entering or removing of the brushes, or enlarging the overall size of the holder over that required for accommodating the two brushes alone. This arrangement is here effected by mounting the paste tube directly in line with and longitudinally under the partition 21 so that the tube will be positioned intermediate and generally parallel to the brush handles. Since the compartments are considerably wider than the brush heads to afford circulation of air about the brush heads, it will be clear that the relatively narrow brush handles will be nor-

5 mally spaced sufficiently apart to permit the po-
sitioning therebetween of a paste tube or powder
can or the like. The supporting means for the
paste tube here comprises a spring clip 31 which
is adapted to clasp the neck or cap portion of
the tube and is mounted on the surface 17 inter-
mediate the clip members 27 and well below the
lower edge of the hood. As will be clear from
Figure 5, and as a further feature of this ar-
rangement, the lateral spacing of the hood from
10 the rear body portion of the holder is such as to
completely overlie the top of the paste tube to
thereby shield the latter against gravitating dust
particles or the like in the air. To facilitate the
15 insertion and withdrawal of the brush handles in
and from the clips 27, in view of the closeness of
the paste tube mounting, the clips 27 may as
here shown be formed to open angularly outward
from the surface 17 and from the tube.

20 Means of ventilation are also provided in the
hood for insuring a circulation of air through
and about the brush heads. As here shown the
opposite ends 32 and 33 of the hood are provided
adjacent the top of the brush compartments
25 with openings 34 which serve, together with the
open bottom of the hood, to promote a constant
flow of fresh air through the compartments.
The openings 34 are preferably sloped outwardly
and downwardly from the compartments so as
30 to prevent the gravitation of dust particles there-
through and into the compartments.

35 Attachment of the holder to wall 15 may be
effected as here shown by providing in the rear
surface 14 of the holder a dove-tailed recess 36
which is arranged for detachable, interfitting
connection with a flanged bracket 37 fixedly sup-
ported on the wall.

40 A modified form of the invention is shown in
Figures 4 to 6 wherein the brushes and paste
tube are supported by an auxiliary band mem-
ber 38 and no permanent attachment of either
brush clips or wall fastening means need be
made to the main body portion of the holder.
As here shown the member 38 is mounted about
45 the holder portion 13' for relative longitudinal
movement thereto and is provided with a pair
of depressed screw receiving portions 39 in the
rear side 41 thereof for attaching the band mem-
ber to the wall 15. Preferably the rear portion
50 14' of the holder member is provided adjacent
the upper end 16' thereof with a rearwardly ex-
tending boss 40 for engaging the wall 15 and
serving, together with depressed portions 39, to
55 maintain the holder portion 13' spaced from
the wall. Arranged at the forward side 42
of the band member 38 is a set of brush and tube
supporting clips 27' and 31' which may, in the
instance where the band may be of spring metal,
be formed as here shown as an integral part of
60 the band. Thus in this form of the invention the
support of the holder and of the brushes and tube
is provided entirely by the band 38 and inde-
pendent of the hood. As a result, the hood may
be raised from a normally seated position with
65 the end walls 32' and 33' thereof resting on

the forward side 42 of the band to a detached
position for permitting ready cleaning thereof
and maintenance of the various parts in sanitary
condition.

5 I claim:

1. In a device of the character described, a
backing member, a hood depending from the up-
per portion of said member and defining there-
with an inverted receptacle, a partition extending
10 between said member and hood dividing said re-
ceptacle into individual compartments, means
for supporting tooth brushes with the head por-
tions thereof extended into said compartments,
and means for mounting a tooth paste tube or
15 the like directly under and aligned with said
partition.

2. In a device of the character described, a
body member defining a chamber and having a
partition dividing said chamber into individual
compartments, means for supporting tooth
20 brushes with the head portions thereof positioned
in said compartments and with the handle por-
tions thereof extending from said compartments
with said handle portions in spaced relation, and
means for mounting a tooth paste tube or the
25 like centrally under and in alignment with said
partition and between said brush handles.

3. In a device of the character described, a
body member defining a chamber and having a
partition dividing said chamber into individual
30 compartments, means for supporting tooth
brushes with the head portions thereof positioned
in said compartments and with the han-
dle portions thereof extending from said com-
partments with said handle portions in spaced
35 relation, and means for mounting a tooth paste
tube or the like centrally under and in align-
ment with said partition and between said brush
handles, said first named means comprising
40 members each providing a receiving opening for
engaging and holding a brush handle and pro-
viding for the entrance of a handle thereto side-
wise and in the direction of said second named
means.

4. In a device of the character described, a body
45 member, a hood therefor, a partition connecting
said member and hood defining a pair of in-
dividual compartments and being terminated
within the open end of the hood, means for sup-
porting tooth brushes with the head portions
50 thereof extended into said compartments, and
means for mounting a tooth paste tube or the
like adjacent and longitudinally aligned with
said partition and spaced from the open end of
but covered by said hood.

5. In a device of the character described, a
body member, a hood therefor, a band embracing
said member and arranged for attachment to a
wall, and means carried by said band for sup-
porting a tooth brush under said hood, said body
60 member and hood being slideable relative to said
band to permit movement thereof to covering or
uncovering relation with respect to said tooth
brush.

ALFRED F. BORBA. 65
